TOILET PAPER ROLLER ATTACHMENT

Anestis Foltis, Jackson Heights, N. Y.

Application February 6, 1946, Serial No. 645,810

2 Claims. (Cl. 242—55.2)

1

This invention relates to toilet paper holder attachments, and more particularly to an attachment for facilitating the insertion and removal of a roll of toilet paper into and out of its recessed fixture.

In the past it has been difficult to apply and remove a toilet paper holder into its bearings within a recessed fixture. Each time a roll of toilet paper is applied into position within a recessed fixture, the holder must be removed, the tubular core of the used roll must be removed from the holder, the new roll inserted upon the holder, and the holder and roll inserted into the fixture. In such types of holder, one trunnion is spring-actuated and must be kept compressed during insertion and removal. It is inconvenient to hold the holder under spring tension and often results in the breaking of the finger nails of an operator for the space between the end of the holder and the adjacent wall of the fixture recess is relatively small. It is therefore the main feature of this invention to provide an attachment by which the insertion and removal of a toilet paper holder into and out of its fixture may be easily and safely performed.

Another feature of the invention resides in a toilet paper holder attachment having a portion which may be attached to one end of the holder without interference with the roll of paper when mounted thereon, and from which a manipulating portion extends for a distance as to be within reach of the fingers of the hand of an operator when the holder is in its operative position within a recessed fixture.

A further feature of the invention is to provide an attachment which may be fitted to toilet paper holders now in use; which is easy to apply in position upon one end of a holder; and which is simple and inexpensive of manufacture.

is simple and inexpensive of manufacture. Other novel features of the invention will become apparent as the following specification is read in conjunction with the accompanying drawings, in which

Figure 1 is a perspective view of a toilet paper holder with one form of my invention in use thereon, the recessed toilet paper roll fixture and hand of an operator being shown in dot and dash lines.

Figure 2 is a side elevation of the attachment in position upon one end of a toilet paper holder, a portion of the attachment being shown in section.

Figure 3 is an end elevational view

Referring to the drawings by reference characters and at present to the form of the invention.

2

tion illustrated in Figures 1 to 3 inclusive, the numeral designates a toilet paper holder in roller form of conventional construction which includes a cylindrical body 11 having a fixed trunnion 12 extending axially from one end thereof. Slidable in the other end of the body 11 is a plunger 13 which is normally urged in an outwardly direction by an expansion spring 14, the movement of the plunger being limited by a pin 15 extending through the body and through an elongated slot 16 in the plunger. The outer end of the plunger 13 is provided with a reduced trunnion 17. To insert the roller 10 into the bearings of a recessed built-in fixture 18 necessitates the inward sliding of the plunger 13 with respect to the body 11 and in instances where the roll of paper 19 is mounted on the roller 10, difficulty is experienced in sliding the roller into the recessed fixture and also in effecting a removal of the roller from the fixture.

To facilitate the insertion and removal of the roller, I provide an attachment 20. The attachment 20 includes a cylindrical body 21 which is open at both ends and split lengthwise as at 22. 25 The material from which the cylindrical body 21 is constructed is resilient and may either be metal or plastic. Formed integral with the outer end of the body 21 adjacent the walls of the slit 22 are inwardly extending stop fingers 23. The 30 inner edge of the body 21 is outwardly flared and terminates in a bead 24 to facilitate the easy insertion of the cylindrical body 21 upon the roller 10 in a manner to be presently explained.

35 Integral with the body 21 at the outer edge thereof is a handle 25 which extends radially with respect to the axis of the body 21. The handle at its connection with the body is outwardly offset as at 26.

40 In use, the attachment 20 is fitted to the end of the roller 10 having the fixed trunnion 12, by slidably inserting the split body 21 over the end of the roller as best illustrated in Figure 2. Inward movement of the body 21 relative to the roller is limited by engagement of the stop fingers 23 which abut the adjacent flat end of the roller. With the attachment in position, a roll of toilet paper may be slid over the end of the roller from which the plunger 13 extends and 50 when the roll is positioned upon the roller the operator, by grasping the handle 25, may insert the roller and the roll as a unit into the recess of the fixture 18, the operator pressing upon the handle to effect a retraction of the plunger 13, 55 it being understood that the end of the trunnion

nion 17 is bearing against the adjacent wall of the recess of the fixture. The operator pushes sideways on the handle until the trunnions 12 and 17 enter their respective bearings, at which time the plunger 13 is moved to an extended position by the spring 14 and the roller and the roll are in locked position within the fixture.

To remove the roller from the fixture to replace a used roll with a full roll, the operator presses sideways upon the handle 25 to effect a disengagement of the trunnions with their respective bearings and at which time the roller may be lifted from the fixture. By reason of the attachment, the roller may be easily inserted and removed from the fixture without likelihood of breaking of the finger nails of an operator for it will be appreciated that the space between the ends of the roller and the walls of the recess is relatively small and prevents the free insertion of the fingers of the hand.

While I have shown and described what I consider to be the most practical embodiments of my invention, I wish it to be understood that such changes in construction, material and design as come within the scope of the appended claims may be resorted to if desired without departing from the spirit of the invention.

Having thus described my invention, what I claim as new and desire to secure by Letters Patent is:

- 5 1. A toilet paper roller attachment comprising a split resilient cylindrical body adapted to be attached to one end of a toilet paper roller, said body having a bead along the edge at one end and bent over stop fingers at the opposite end, and a handle connected to the last-named end of said body and extending radially outwardly relative to the axis thereof, the handle being offset from the plane of said end.
- 10 2. A toilet paper roller attachment comprising a split resilient cylindrical body adapted to be attached to one end of a toilet paper roller, a handle connected to one end of said body and extending radially outwardly relative to the axis thereof, and stop means adjacent one end of the cylindrical body adapted to engage the adjacent end of the roller onto which it is fitted for limiting the insertion of the roller into the body.

ANESTIS FOLTIS.
